UNITED STATES PATENT OFFICE.

HARRY J. MORRIS, OF PASADENA, CALIFORNIA.

ORTHOPEDIC APPLIANCE.

Application filed February 9, 1925. Serial No. 7,915.

This invention relates to a brace for the correction of either bow-legs or knock-knees, as the appliance is so constructed that it can be used for either, and has, for one of its objects, to exert constant force tending to straighten the limb, as the wearer stands or walks, or while lying with the limbs in an extended position, and provide a knee-joint that will permit of free pivotal action under stress.

A further object is to provide a construction that will relieve the force or tension upon the limbs when the knees are flexed and the limbs form a right angle, as in a sitting posture; also, to embody the desirable features of simplicity, strength and lightness.

With these objects in view, the invention consists in certain novel and useful features of construction and combination of parts, as herein described and claimed; and in order that it may be fully understood reference is to be had to the accompanying drawing, in which:

Figure 1, is a vertical side-view embodying the invention as applied to the limb.

Figure 2, is a view of the invention showing it applied to the limb, as in sitting posture.

Figure 3, is a front view of the invention.

Figure 4, is a fragmentary, enlarged, perspective view of the pivotal connection in detail.

In the said drawing, 1 indicates the thigh member, and 2, the shin member of an orthopedic appliance called a limb straightener, said members being pivotally connected at 8. 3 indicates spring steel strips formed in a curve to meet the contour of the circumference of the leg and attached transversely to opposite ends of said thigh and shin members for the purpose of attaching pads 4. 5 also indicates thin spring steel strips, as described above, for the purpose of attaching straps 6 thereto, by which the appliance is attached to the leg through the medium of a buckle 7.

Portion 1 and portion 2 are constructed of high-grade spring steel, of approximately 35/1000 inch in thickness and $\frac{3}{4}$ inch in width, formed in a longitudinal curve and pivotally connected at 8 to allow free articulation while walking, but at the same time said pivotal connection is under constant side stress as the curvature of the appliance is to be applied diametrically opposite that of the leg, whereupon it is then sprung in to

meet or conform to the longitudinal curvature of the leg and held in that position through the medium of straps 6, thus causing a constant pulling force diametrically against the longitudinal curvature of said leg, tending to straighten same.

To allow the pulling force on straps 6 to be relaxed for the purpose of giving relief to the wearer without necessitating the removal of the appliance from the limb, the knee-joint, Fig. 4, is provided with suitable shaft 9 which transpierces portions 1 and 2 with suitable heads 10 securely mounted on either end thereof, portion 1 extending downwardly beyond shaft 9 and terminating in a curve 11 for abutment against portion 2 and portion 2 extending upwardly beyond shaft 9 and terminates in curve 12 for abutment against portion 1 for the purpose of exerting pressure on shaft heads 10. The bores or passages 13 should be sufficiently large to permit the shaft 9 some latitude, thus allowing slide movement to portions 1 and 2 when the knee-joint is bent to a right angle which will allow both portions 1 and 2 to lie close to and follow the general contour of the wearer's knee 14.

From the above description it will be apparent that I have produced an orthopedic appliance having external strap connections for continuously exerting pulling force against longitudinal curvature of the leg of the wearer to straighten same as a whole, and by which the tension can be quickly and effectively relieved when desired by bending or flexing the knees to a right angle, and while I have illustrated and described the preferred embodiments of the invention, it is to be understood that I reserve the right to make all changes falling within the spirit and scope of the appended claims.

What I claim as new, and desire to secure by Letters Patent, is:

1. A limb straightener comprising a thigh member and a shin member pivotally connected together to constitute a knee-joint, said knee-joint having a suitable shaft mounted in borings in both thigh and shin members with suitable heads mounted on either end of said shaft, said shaft being long enough and said borings being large enough to permit lateral movement on said shaft of both thigh and shin members when said knee-joint is flexed, forming a right angle; said thigh member extending somewhat below said pivotal connection and ending in

a curve and abutting against said shin member and said shin member extending somewhat above said pivotal connection and ending in a curve and abutting against said 5 thigh member causing pressure to be exerted against said shaft heads when said limb straightener is fully or partly extended, thus allowing pivotal action under stress by forcing the bends that form that portion of the 10 pivotal section.

2. A limb straightener, comprising a thigh member and a shin member pivotally connected together to constitute a knee-joint, said knee joint having a suitable shaft

mounted in borings in both thigh and shin members with suitable heads mounted on either end of said shaft to hold said shin and thigh members together, said shin and thigh members forming a bowed section with cross-bars firmly mounted on said thigh and shin members and curved to meet the contour of the circumference of the leg of the wearer and carrying straps to encircle the said leg, said strap when girted to said leg reverse the said bowed section forcing it to 20 conform to that of said leg, which applies a constant pull on said straps.

HARRY J. MORRIS.
